UNITED STATES PATENT OFFICE.

THOMAS CROSS EDWARDS, OF CHATHAM, CANADA.

SAD-IRON.

SPECIFICATION forming part of Letters Patent No. 535,576, dated March 12, 1895.

Application filed May 11, 1894. Serial No. 510,870. (No model.)

To all whom it may concern:

Be it known that I, THOMAS CROSS EDWARDS, a subject of the Queen of Great Britain, and a resident of Chatham, in the Province of Ontario, Dominion of Canada, have invented certain new and useful Improvements in Self-Heating Sad-Irons, of which the following is a specification.

My invention relates to self-heating sad-
10 irons which carry a suitable burner and reser-
voir and which are trunnioned in the handle
to permit them to be readily reversed as soon
as one face becomes cool and the other is
heated.

15 My invention consists in certain novel fea-
tures of construction to be hereinafter pointed
out in the claims, the same being first fully
described with reference to the accompanying
drawings, in which—

20 Figure I is a perspective view of a sad-iron
embodying my improvements, and Figs. II,
III and IV are respectively an end view, a
vertical longitudinal section, and a vertical
transverse section of the same. Fig. V is a
25 plan of one of the two similar irons which
form the body of the sad-iron. Fig. VI is a
detail sectional view of a portion of the shell
and iron, showing the flange on the shell fit-
ting in the groove formed for it in one of the
30 irons. Fig. VII is a detail perspective view
of a portion of the shell, and the trunnion
which has its bearing therein. Fig. VIII is a
detail view of a part of one of the irons, show-
ing the groove formed therein for the recep-
35 tion of the flange on the shell.

The device consists of a body 1, a non-heat
conducting handle 2, and an interposed shield
1^a, the body being provided at one end with
a trunnion 3 which enters a bearing ring 4,
40 on an arm 5, while at the other end a cylin-
drical trunnion 6 cast integral with the arm
7, has bearing in the body at 8. The arms 5
and 7 have, at their upper ends, steps 5^a and
7^a and upon which the ends of handle 2 are
45 secured by means of screws 2^a. The shield 1^a
has its opposite ends inserted between the
ends of handle 2 and the steps 5^a and 7^a.

50 Referring to Fig. III, 9 represents a burner,
which projects into the iron and is supported
in proper relation to heat the same, by means
of a thimble 10, which fits snugly into the cy-
lindrical trunnion 6, and is provided with

perforations 11, for the purpose of admitting
air to support combustion and also to prevent
the undue heating of the parts beyond said 55
trunnion. The burner 9 has an upwardly ex-
tending tube 12 surmounted by a reservoir 13
and tube 12 has integral extension 14 within
the reservoir for the purpose of preventing
the escape of the fuel, otherwise than by ab- 60
sorption through the wick 15. The reservoir
is closed by a screw cap 16, and is held in up-
right position by means of a pair of spring
jaws 12^a attached to the tube 12 below the
reservoir and engaging the arm 7 in such a 65
way as to prevent the turning of the thimble
10 in the trunnion 6.

The body consists in a central shell 17 hav-
ing formed on its edges projections 18 with
intervening air spaces 19, and two similarly 70
formed irons 20 with plane smoothing faces,
and convex inner surfaces having recesses 20^a
the convexity adding weight and bulk and
increasing the heat retaining qualities and
the recesses increasing the facility for heat- 75
ing the irons by the burner. The irons have
oppositely projecting and overlapped ears 21
through the medium of which they are se-
cured to the central shell 17 by screws 22. In
order to prevent displacement of the irons 20 80
at their ends they have formed upon them at
one end lugs 23, which enter recesses at one
end of the shell 17 in the lugs 18, while at the
opposite end, the irons have seats 23^a to re-
ceive flanges 17^a on the shell. It is prefer- 85
able to form in the bearing ring 4 a semi-cir-
cumferential recess 24, which leaves shoul-
ders 24^a in such position as to engage a pin
25 radiating from the trunnion 3, and arrest
the turning of the body in either direction 90
when the irons are brought into the proper
plane. In order to facilitate turning the
body to interchange the irons, a reversing le-
ver 26 is hinged on a normally horizontal pin
27, which passes transversely through the 95
trunnion 3 and permits said lever to project
approximately at right angles to the trunnion
whereby it is adapted to control the movement
of said iron, and also to permit said lever, af-
ter the iron has reached its limit of movement 100
in either direction, to turn upward against
the arm 5 and enter a socket 26^a, formed upon
said arm, for the purpose of preventing the
lever from moving laterally. The lever is se-

cured in this socket 26^a by means of a pair of spring jaws 28 between which it may be forced in the act of entering the socket, and these spring jaws are held in the proper position by a depression 28^a in the step 5^a, and in which said jaws are held by the handle 2.

I am aware that the general principles of my sad-iron are not broadly new, but it will be observed that the device embraces novel 10 details in construction, which better adapt it to serve the purposes intended and which also make it more economical to manufacture and more durable in use.

Having thus described my invention, the 15 following is what I claim as new therein and desire to secure by Letters Patent:

1. In a self-heating sad-iron the body consisting of the central shell having the burner opening and the two similar plano-convex 20 irons having recessed inner faces and secured to said shell by the ears and screws at the

sides and by the lugs and recesses at one end, and the seats and flanges at the other around the burner opening, as explained.

2. In a self-heating sad iron, the combination of a handle 2, a body 1 trunnioned in said handle and having a burner, said body consisting of a central hollow shell into which the burner projects and having on its edges projections 18 forming intervening air spaces 19, and the two similarly formed irons 20 resting upon the projections 18, secured by oppositely projecting overlapping ears 21 and screws 22, and prevented from displacement at the ends by lugs 23 which enter recesses in 30 two projections 18, all substantially as and for the purposes set forth.

THOMAS CROSS EDWARDS.
